METHOD OF MAKING A ROAD TOOL

Jasper G. Tullis, Cleveland, Ohio, assignor to
The Cleveland Formgrader Company, Cleve-
land, Ohio, a corporation of Ohio

Application July 30, 1932. Serial No. 626,461

4 Claims. (Cl. 76—101)

This invention relates to a straight edge or templet for gauging hard surface roadways and the like and is a continuation in part of my co-pending application Ser. No. 531,049, filed April 18, 1931. As there more fully described, in the construction of concrete and other paved roadway surfaces for high speed vehicular traffic, much greater precision as to regularity and smoothness of the pavement surface is required, and one of the principal objects of the present invention is the provision of a straight edge or templet having a true and precise gauging face for gauging more accurately such pavement surface as the surfacing material is being spread. Another object is to provide a straight edge, the gauging face of which will retain an accurate configuration when subjected to rough usage and to various extremes of temperature.

Another object is to provide a folded sheet metal straight edge having a gauging face of which the entire surface lies in the same plane and contains none of the surface depressions or irregularities common to rolled sheet metal.

Still another object resides in the method of forming a gauging face of the desired shape on a folded sheet metal gauging tool.

Other objects and features of the invention will become apparent from the following description, wherein reference is made to the drawing.

In the drawing, Fig. 1 is a perspective view of one form of the tool embodying the principles of the present invention;

Fig. 2 is a perspective view of a sheet suitable for forming the tool illustrated in Fig. 1;

Fig. 3 is a diagrammatic perspective view illustrating one step in the method of forming the gauging surface of the tool;

Fig. 4 is an enlarged diagrammatic perspective view of the sheet metal stock, illustrating the result produced by the step illustrated in Fig. 3;

Fig. 5 is a sectional view of the tool illustrated in Fig. 1 and is taken on a plane indicated by the line 5—5 thereof, and

Figs. 6 and 7 are, respectively, diagrammatic sectional views illustrating a modified method of forming the gauging surface of the tool and the modified form of tool resulting therefrom.

Referring to Fig. 1, which illustrates a straight edge tool embodying the principles of the present invention, the tool comprises a head 1 to which is attached a handle 2, the handle being of sufficient length to enable the operator to stand at one edge of the pavement and position the

straight edge slightly past the center thereof. The handle 2 and the body 1 are preferably made of aluminum so as to render them as light as possible and to reduce stresses due to changes in temperature.

One general use of the tool and the manner of folding the metal to form the same are fully described in my copending application, above identified. As there more fully described, the body 1 may be formed from a rolled strip or sheet of aluminum or other metal 3 illustrated in Fig. 2.

The commercial sheet metal, as it comes from the various mills, is rolled to present a fairly regular and smooth surface. However, in the rolling operation, this surface is formed with slight depressions, such as indicated at 4, these depressions extending various distances both longitudinally and transversely of the face of the strip. When such a strip is folded, as described in my co-pending application, to form a straight edge, many of these depressions are of such width that they extend entirely across the gauging face. Consequently, when the finished straight edge or templet is placed against a master gauge, a considerable amount of light can be seen between the gauging surfaces of the two. Under most present day roadway specifications, this is objectionable and a straight edge "showing light" when placed against the master gauge, is rejected for use.

Another objection to the use of commercial rolled sheet metal resides in the fact that the rolling of the material compacts the areas surrounding these depressions to a greater degree than the depressed areas themselves and sets up internal stresses. Consequently, when the metal is exposed to different degrees of temperature, there is a tendency for it to warp and twist due to the resulting internal stresses being unevenly distributed. In order to eliminate these depressions and irregularities and to compact the metal to a more even and uniform degree over the entire surface so as to overcome both of the above objections, the present method of forming the gauging surface of the straight edge from the strip stock may be used.

According to this method, which is illustrated in Fig. 3, the sheet is placed between a suitable female die 5 and complementary male die 6 and is impacted thereby under heavy pressure, thus forming a longitudinal central portion of the strip into a gauging surface and partially folding the strip to form the hollow body 1. The face 7 of the female die is a precise and accurate smooth plane surface or a smooth accurate surface of

the particular shape into which the gauging face of the tool or templet is to be formed.

The complementary working face of the die 6 is corrugated, as indicated at 8, by parallel longitudinal corrugations so that upon engagement with the sheet 3, the metal of the sheet is compressed along evenly laterally spaced longitudinal areas. In this same operation of the dies, the margins 9 of the sheet 3 are folded up to partially form the sheet into the proper cross sectional shape.

Referring to Fig. 4, the metal of the portion of the sheet which has been compressed between the dies is caused to flow as indicated by the arrows 10. This action presses out the depressions 4 and other irregularities; indicated by the dotted line in Fig. 4, so that the gauging surface 11 of the sheet engaged by the female die is made to conform accurately with the surface 7 of the die over its entire length and width. This action also effects the setting of the metal as it relieves the internal stresses in the metal resulting from the rolling operation and effects an even and regular distribution of stresses resulting from compression by the dies. Consequently, the gauging face not only conforms to the configuration of the face 7 of the die 5, but also will maintain such formation. The longitudinal ribs 12, formed by this corrugating operation, reinforce the gauging face of the strip and reduce the tendency warp longitudinally. When the sheet is corrugated in this manner, it will withstand great changes in temperature without warping or stressing due to internal strains and will also withstand rough usage in practical use.

After the gauging face has been formed, as described, the margins are bent inwardly and then upwardly, as more fully described in my co-pending application, to form a flange or rib 14 of two thicknesses of the metal stock, the margin along one side of the sheet being folded over the upper end of the margin of the opposite side of the sheet, as indicated at 15, for securing the two margins in juxtaposition. In this manner, a rigid hollow body with a longitudinal reinforcing rib is provided, the gauging surface of which is set to a very precise and accurate configuration.

Referring now to Figs. 6 and 7, a method of forming the gauging face of the straight edge similar to that above described is illustrated. In this method not only is a corrugated working face provided on the male die, but a similar face 16 is provided on the female die so that when the metal is impacted by the dies and folded to produce the straight edge shown in cross section in Fig. 7, the outwardly disposed gauging face 17 is likewise corrugated with small longitudinally

extending parallel corrugations. In many cases, it is desirable that the corrugations on the outer face be somewhat smaller than those on the inner face, so that the cumulative effect is to produce a general plane gauging face, having no transversely extending depressions or irregularities.

As described in my co-pending application, if it is desired to have the rib 14 of greater depth at the center, the sheet may be cut accordingly wider at the central portion, tapering toward the ends.

It is apparent from the foregoing description that the gauging face of the straight edge or templet formed by either of these methods is not only very precise and accurate, but is set so as to maintain its accuracy under various conditions of usage and degrees of temperature.

Having thus described my invention, I claim:

1. A method of forming a straight edge tool from sheet metal stock, comprising supporting a portion of one face of the sheet on a rigid surface and impressing corrugations on the opposite face of the sheet to cause the metal to flow and effect set engagement of the entire first mentioned face with the said surface and folding the sheet into a hollow elongated body with the first mentioned face disposed outwardly thereof to form a gauging face.

2. A method of forming a gauging face for a straight edge tool of the character described from sheet metal stock, comprising supporting a longitudinal face portion of the sheet on a rigid surface and compressing closely spaced portions of the metal on the opposite face of the sheet for effecting set conformation of the first mentioned face and the said rigid surface.

3. A method of forming a gauging face for a gauging tool from sheet metal stock, comprising simultaneously impacting opposite faces of a longitudinal portion of said sheet with rigid corrugated surfaces for causing the metal of said strip to flow to effect conformation of one of said faces with one of said surfaces, and to set said face of the strip in such conformation.

4. A method of forming a straight edge tool of the character described from sheet metal aluminum, comprising supporting a portion of one face of the sheet on a smooth rigid surface and impressing corrugations on the opposite face of the sheet to cause the metal to flow and effect set engagement of the said portion of the first mentioned face with the plane surface over the entire area thereof and folding the sheet into a hollow elongated body with the first mentioned face disposed outwardly thereof to form a gauging surface.

JASPER G. TULLIS.
